DESIGN FOR A COMBINED CIGARETTE CONTAINER AND SUPPORT THEREFOR

Ralph N. Kircher, West Bend, Wis., assignor to West Bend Aluminum Company, West Bend, Wis., a corporation of Wisconsin

Application February 27, 1936, Serial No. 61,374

Term of patent 7 years

To whom it may concern:

Be it known, that I, Ralph N. Kircher, a citizen of the United States, residing at West Bend, in the county of Washington and State of Wisconsin, have invented a new, original and ornamental Design for a Combined Cigarette Container and Support Therefor, of which the following is a specification, reference being had to the accompanying drawing, forming part thereof.

Figure 1 is a view in side elevation of a combined cigarette container and support therefor showing my new design;

I claim:

The ornamental design for a combined cigarette container and support therefor as shown.

RALPH N. KIRCHER.
